CLAIM

The ornamental design for a camera stand base, as shown and described.

DESCRIPTION

The present application is related to U.S. patent application Ser. No. 29/530,172, entitled "Camera," filed on Jun. 14, 2015; U.S. patent application Ser. No. 29/530,171, entitled "A Stand Assembly," filed on Jun. 14, 2015; and U.S. patent application Ser. No. 29/530,170, entitled "A Receiving Element of a Stand Assembly," filed on Jun. 14, 2015, each of which is hereby incorporated by reference in its entirety.

FIG. 1 is a perspective view of a camera stand base showing the new design.

FIG. 2 is a side view of the camera stand base shown in FIG. 1.

FIG. 3 is a bottom view of the camera stand base shown in FIG. 1.

FIG. 4 is a front view of the camera stand base shown in FIG. 1.

FIG. 5 is a top view of the camera stand base shown in FIG. 1.

FIG. 6 is a perspective view of another camera stand base including a mount structure and the camera stand base shown in FIG. 1.

FIG. 7 is a bottom view of the camera stand base shown in FIG. 6.

FIG. 8 is a perspective view of another embodiment of a camera stand base showing the new design.

FIG. 9 is a side view of the camera stand base shown in FIG. 8; and,

(Continued)

FIG. 10 is a perspective view of a camera stand base including a camera, a receiving element, and a camera stand base shown in FIG. 1.

The broken lines in the above described figures depict elements of the camera stand base and environmental features that form no part of the claimed design.
